METHOD OF PRODUCING A DOUBLE-WALLED CONTAINER

Herman K. Kimble, Vineland, N. J.

Application October 9, 1936, Serial No. 104,793

5 Claims. (Cl. 49—82)

This invention relates to double-walled containers and to a method for producing the same.

One of the primary objects of this invention is to provide a double-walled container in which the mouth or neck portion is made of substantial strength so that it is not broken by the shocks and the strains to which it is subjected.

A further object of the invention is to provide a method by which double-walled containers can be economically produced on a commercial scale.

Further objects and advantages of the invention will become more apparent as the following description proceeds particularly when reference is had to the accompanying drawing wherein:

Fig. 1 is a longitudinal sectional view through a container constructed in accordance with the teachings of this invention;

Fig. 2 is a sectional view through the container showing the parts thereof in spaced relation to each other and as they appear before the container is assembled;

Fig. 3 is a longitudinal sectional view through a modified type of outer vessel which might be utilized;

Fig. 4 is a sectional view through a modified type of inner vessel which may be utilized; and

Figs. 5 to 9 inclusive, are fragmentary sectional views showing various modifications of the surfaces at which the parts of the container are sealed together.

In the production of double-walled containers, the practice which is generally followed is to seal one vessel within another. The methods now practiced require costly and slow manipulation of the vessels and produce containers which are particularly weak at the termination of the necks or open ends of the containers where the seals between the two vessels are effected.

The shock attending the handling of the container, particularly when the latter is filled, subjects the seal between the two vessels to the entire strain, and since the neck is unprotected so that a closure may be applied to the container, the container is thus subjected to the greatest strain at its weakest point.

To eliminate these disadvantages, the present invention contemplates the production of a double-walled container in which the seals are protected and the neck or section of the container to which a closure is to be applied is made the strongest part of the container. Further, the invention contemplates the provision of a method whereby the seals between the inner and outer vessels may be effected in an evacuated cham-

ber so that the double-walled containers may be economically produced on a commercial scale.

Referring now to the drawing wherein like reference characters designate corresponding parts throughout all views, the numeral 10 designates generally one of the elements or parts which are utilized in producing the container. The part 10 comprises a tubular member 11 which terminates at one end in a mouth 12 and at its other end in an edge or surface 13 for a purpose which will later be described. The tubular member 11 is also provided with a depending skirt 14 which terminates in an edge or surface 15, the purpose of which will also later be described.

The element 10 may be made in any desired manner as by molding, pressing or the like, and is preferably provided exteriorly adjacent the mouth 12 with screw threads 16 so that a screw cap closure may be utilized, if desired. Obviously, the mouth of the member 10 may be closed by an ordinary cork in accordance with the usual practice.

The numeral 20 designates the inner vessel of the double-walled container and this vessel is provided with the open end 21 which is defined by an edge or surface 22. The edge or surface 22 is welded or sealed to the surface 13 so that the part 10 is thus sealed to and becomes substantially integral with the vessel 20. The surfaces or edges 13 and 22 are made of a thickness suitable for heat welding or may be made somewhat thicker to provide a wider surface for soldering or the like.

After the vessel 20 is sealed to the part 10, the outside surface of the vessel 20 is coated with a silver or other deposit as is also the inside surface of the vessel 25 which constitutes the outer vessel of the double-walled container. The vessel 25 is provided with an edge or surface 26 which is adapted to be sealed to the edge 15 of the part 10, and this sealing may be effected either by heat welding or by solder or other suitable sealing means.

It will be apparent that when the inner vessel 20 is sealed to the tubular element 11 and the outer vessel 25 is sealed to the skirt 14, a double-walled container such as illustrated in Fig. 1 is produced. It will be noted that while the body portion of the container is double-walled, the mouth or neck portion thereof is defined by a single wall. Thus the mouth or neck of the vessel which is generally exposed and subjected to the greatest shocks, becomes the strongest part of the container, while the seals between

the inner and outer vessels and the portion 10 of the container are located a substantial distance from the mouth of the container with the result that they are protected by the casing in 5 which the double-walled container is generally located.

It is a feature of the invention that the sealing of the outer vessel to the skirt 14 may be effected in an evacuated chamber. The edges 15 10 and 26 may be heated while the chamber is under negative pressure, or the edges may first be heated and then the chamber brought under negative pressure with the result that a negative pressure exists in the space between the inner 15 and outer vessels. It will be understood, of course, that the edges 15 and 26 are heated until they become sufficiently plastic so that they may be welded together.

Instead of effecting a sealing of the inner and 20 outer vessels to the part 10 by heat welding, this sealing may be effected by an aluminum solder or some other similar soldering compound. This is accomplished by applying the soldering compound at a predetermined temperature to the 25 edges 13 and 22 and the edges 15 and 26, while the parts 10, 20 and 25 of the container are within the chamber under negative pressure.

If desired, the sealing of the outer vessel to the part 10 may be done under atmospheric pressure, 30 the insulating medium for the double-walled container being placed in the space between the inner and outer vessels before the sealing is commenced. Any insulating material may be used such for example, as glass wool, mineral 35 wool, Silocel or the like.

In Fig. 3 there is disclosed a slightly modified type of outer vessel which may, if desired, be utilized instead of the outer vessel shown in Fig. 2. This modified type of outer vessel is provided with 40 a tubulation 30 which may be placed at any part of the vessel but can most conveniently be located as shown, at the bottom of the vessel.

This tubulation serves a two-fold purpose 45 namely, to admit air between the inner and outer vessels during the welding or sealing process and as a fitting to which an evacuating means may be attached to exhaust the air between the inner and outer vessels after the sealing is effected. After the space between the inner and outer vessels has been brought to the desired negative 50 pressure, the tubulation 30 is sealed by applying heat to the same in a well-known manner.

In Fig. 4 a slightly modified type of inner vessel is illustrated. In this embodiment of the invention the mouth and the inner vessel are made 55 integral this being accomplished by any of the well-known methods such, for example, as the press and blow method. It will be obvious that with the part 10^a integral with the part 20^a, an outer vessel may be sealed to the skirt 14 in any 60 of the manners previously described.

As previously mentioned, the edges between which sealing is to be effected are made of a thickness suitable for heat welding or somewhat 65 thicker to present a wider surface for solder or other sealing means. Additionally, these edges may be formed in any of the manners illustrated in Figs. 5 to 9 inclusive depending upon the manner in which the edges are to be sealed together.

70 From the above it will be apparent that the invention provides a double-walled container in which the neck portion or that portion which is unprotected and subjected to the most shocks is made of a single thickness and thus sufficiently 75 strong so as to resist the shocks and strains to

which it is subjected. Additionally, the invention provides a method whereby the negative pressure between the inner and outer vessels may be obtained by sealing the outer vessel of the container to the remaining part thereof in a chamber which is maintained under the desired negative pressure. The methods may be economically carried out on a commercial scale thus providing for the production of double-walled containers at substantially less cost than has heretofore been possible. 10

It might be noted that by producing a double-walled container in accordance with the teachings of this invention, the spacers which are usually located between the inner and outer vessels may, if desired, be eliminated. The fact that the inner and outer vessels are rigidly sealed to the preformed part 10, insures that the vessels will be securely held in spaced relation to each other. 20

While the invention has been described with some detail, it is to be understood that the description is for the purposes of illustration only and the right is reserved to make such changes in the details of construction and the steps of 25 the method as will fall within the purview of the attached claims.

What I claim as my invention is:

1. The method of forming a double-walled container which consists in forming a neck section 30 having spaced apart free edges one of which surrounds the other, and thereafter sealing a vessel to each of the spaced apart edges of the said neck section.

2. The method of forming a double-walled container which consists in forming a combined neck and mouth section, and thereafter sealing inner and outer vessels to one end of said mouth and neck section.

3. The method of producing a double-walled 40 container which consists in forming a neck section having a free edge portion surrounded by a depending skirt, then sealing an inner vessel to the said free edge portion of the neck section, and thereafter sealing an outer vessel to the free edge 45 portion of the depending skirt.

4. The method of forming a double-walled container which consists in forming a neck section having a free edge surrounded by a depending skirt, then sealing an inner vessel to the said 50 free edge of the neck section, thereafter sealing an outer vessel to the free edge of the depending skirt, and exhausting the air from the space between the two vessels.

5. A method of producing a double-walled glass 55 container which consists in forming a single-walled neck section having a depending skirt connected to the neck section in a plane spaced from the open end thereof, said neck having an inner vessel integrally united thereto and said skirt 60 having its free edge spaced radially outward from the neck and having a cross section substantially greater than the cross section of the inner vessel, the skirt terminating adjacent the zone of union of the neck and inner vessel, forming 65 an outer vessel having a closed end and an open end, the latter end having dimensions corresponding to those of the free edge of the depending skirt, the outer vessel being of a length to permit its open end to abut the free edge of the 70 skirt, while the closed end thereof is spaced from the inner vessel, and thereafter uniting the outer vessel to the free edge of the depending skirt.
